UNITED STATES PATENT OFFICE

KATHERINE NICHOLS AND RICHARD BETTIEN, OF CHICAGO, ILLINOIS; SAID BETTIEN
ASSIGNOR TO SAID NICHOLS

TELEPHONE

Application filed April 17, 1931. Serial No. 530,867.

This invention relates to telephones in general and particularly to telephones of the wall type which are used in pay stations and booths.

- 5 The primary object of the invention is to provide a telephone instrument which has a pair of properly spaced receivers which are rigidly connected to a transmitter and pivotally connected to the instrument base where-
10 by the user is compelled to talk directly into the transmitter without coming in personal contact with it, while the receivers are arranged in proper position relative to the head of the user.
15 Another object is to provide a new and novel telephone instrument which is provided with connected spaced receivers to which a transmitter is rigidly connected and comprising a single unit which is pivotally connected to a suitable support whereby the receivers and the transmitter, while remaining in constant position relative to each other, may be swung as a unit to various angular positions.
20 25 A still further object is to provide a new and novel method of establishing the various electrical connections between the instrument and the line wires.

Numerous other objects and advantages 30 will be apparent throughout the progress of the following specification.

Fig. 1 is a detail sectional view of the improved apparatus on the line 1—1 of Fig. 2.

Fig. 2 is a detail elevation showing the ap- 35 paratus supported on a wall.

Fig. 3 is a detail sectional view on the line 3—3 of Fig. 1.

Referring to the drawings, 5 designates a suitable base which is attached to the wall and 40 carries a housing 6. A tubular sleeve or shell 7 is operatively connected to the housing and is provided with slots 8, 8 through which pins 9 extend. The pins 9 are operatively connected to a stud 10, which stud 45 is held in the shell 7 by the member 11. Movement of the stud 10 is accomplished by moving the pins 9 forwardly and rearwardly, the movement being restricted by the length of the slots 8.

50 A member 12 comprising spaced arms 13,

is pivotally connected to the shell 7 as indicated at 14, Fig. 2. The lower ends of the arms 13 are rigidly connected to a coupling member 15 as indicated at 16, Fig. 1.

Curved or bent tubular arms 17, Fig. 2, 55 are connected to the coupling member 15 near their upper ends, and leaf springs 18, each supporting a receiver 19, are connected to the free ends of the arms 17.

A transmitter 21 is rigidly connected to the coupling member 15 and is suitably spaced 60 between the receivers 19. The normal space or positions of the two receivers is slightly less than the normal head width, and the leaf 65 springs 18 tend to hold the receivers comfortably to the ears of a user when the instrument is in use. The pivotal point 14 permits the receivers and the transmitter to be swung from down normal non-use position as shown in Figs. 1 and 4, to operating or 70 using position as shown in dotted lines in Fig. 1.

The circuit wires from the receivers extend through the flexible conduits 20 and tubular arms 17 into the hollow body portion of the 75 coupling member 15 where they are incorporated with the transmitter circuit wires to form a cord, not shown. This cord passes through one of the tubular arms 13 and into the stud 10. The stud 10 is provided with 80 an opening 22 through which the cord passes and leads inside of the housing 6 where it is operatively connected to the various elements arranged inside of the housing.

These elements comprise a resistance coil 85 23, Fig. 1, and a fiber terminal plug 24 which are supported on a plate member 25. The terminal plug 24 has a series of binding screws 26, Fig. 3, through which the various electrical connections between the instrument 90 and the line wires are made. Contact plates 27 and 28 are fastened to the terminal plug 24 for completing the circuit, the contact plate 27 being elongated to extend across the path of the stud 10. These contact plates 95 are included in the signal circuit and when the instrument is in normal position, as shown in Fig. 1, a conical fiber tip 29 on the stud 10 contacts with the contact plate 27 and holds it out of contact with its companion contact 100

plate 28, thereby breaking the signal circuit.

In using the device, the receivers and the connected transmitter are swung from the position shown in full lines to the position 5 shown in dotted lines in Fig. 1. The pins 9 are then pulled outwardly to the right, Fig. 1, to move the stud 10 and permitting the contact plate 27 to engage the contact plate 28 to complete the circuit.

10 The instrument may be used in connection with a coin box 30 having the usual coin receiving openings 31. The coin box is preferably arranged between the receivers as shown in Fig. 2. The instrument may also 15 be hooked up for dial operation, the dial 32 being operatively connected to a part of the housing 6. The connections to the coin box and to the dial are made in the usual manner so further description as to these 20 electrical connections will not be made.

In operating the device, the receivers and the cooperating transmitter are swung from the position shown in full lines to the position shown in dotted lines in Fig. 1. The 25 receivers are applied across the head of a user when a coin is inserted in the proper opening 31. The insertion of the coin makes the proper connection, and when the pins 9 are moved to the right, Fig. 1, the circuit is 30 completed between the plates 27 and 28. The number is then dialed on the dial 32.

When the user has finished, the pins 9 are forced inwardly, causing the fiber tip 29 on the stud 10 to move the lower contact plate 35 27 forwardly to the position shown in Fig. 1, the receivers and transmitter being permitted to drop down in normal position as shown in full lines in Fig. 1.

The invention provides a convenient and 40 efficient telephone device which causes the user to speak directly into the transmitter, but prevents direct contact therewith. The receivers are properly held in position on the head of the user, permitting the user to 45 have free use of his hands for dialing. The slideable movement of the stud causes a positive and efficient completion or breaking up of the circuit.

Changes may be made in the form, construction, and arrangement of the various parts without departing from the spirit of the invention or sacrificing any of its advantages, and the right is hereby reserved to make 55 all such changes as fairly fall within the scope of the following claims.

The invention is hereby claimed as follows:

1. In a device of the class described, a unit 60 comprising a pair of receivers, a transmitter operatively connected to the receivers, means for pivotally connecting said unit to a telephone housing, and manually operated means independent of the pivotal movement of the unit for controlling the signal circuit of the telephone system.

65 2. In a device of the class described, a

housing, a pair of arms pivotally connected to the housing, receivers flexibly connected to said arms, resilient means for holding the receivers in a predetermined spaced position, a transmitter fixed to said arms and spaced 70 therebetween, said transmitter being movable with the arms, and means operating independently of the arms for controlling the signal circuit of a telephone system.

3. In a device of the class described, a housing, a receiver and a transmitter operatively connected to said housing, means inside of said housing for controlling the signal circuit of a telephone system, said means including a 75 slideable plug and means for limiting the sliding movement of the plug and preventing removal thereof.

4. In a device of the class described, a housing, a coupling member, arms fixed to said coupling member and pivotally connected to 80 said housing, a pair of outwardly extending arms fixed to said coupling member, receivers flexibly connected to said last named arms, a transmitter arranged between said receivers and rigidly connected to said coupling member, and additional means operated independently of any of said other means for controlling the signal circuit of a telephone system.

KATHERINE NICHOLS. 95
RICHARD BETTIEN.
